United States Patent

Des. 236,108
Patented July 29, 1975

236,108

MODULAR BUILDING

Berne A. Watkins, 76 Cambridge Road,
Glenmont, N.Y. 12077

Filed Nov. 4, 1971, Ser. No. 195,904

Term of patent 14 years

Int. Cl. D25—03

U.S. Cl. D13—1 R

FIG. 1.

FIG. 2.

FIG. 1 is a perspective view of a modular building unit of the modular building shown in FIG. 2, and

FIG. 2 is a perspective view of a modular building showing my new design.

The side and rear of the modular building unit of FIG. 1 and also of the modular building of FIG. 2 are like the front and side view shown.

I claim:

The ornamental design for a modular building, as shown and described.
